FLOOR SCRUBBING AND DRYING MACHINE

Edward O. Norris, Westport, Conn.

Application February 15, 1946, Serial No. 647,920

4 Claims. (Cl. 15—320)

1

This invention relates to machines for scrubbing floors, walls and the like, and has for its object to provide a novel and improved machine for supplying a cleaning liquid to the surface to be scrubbed and for drying such surface by the application of suction after the scrubbing operation.

Another object of the invention is to provide a portable scrubbing machine of the above type which may be connected to any available source of cleaning liquid and to any available waste receptacle or drain, and in which all of the mechanisms necessary to the scrubbing and drying operations are contained within the machine itself.

Another object of the invention is to provide an improved hand-controlled valve mechanism for a scrubbing machine of the above type whereby a simple unidirectional pump contained within the machine may be utilized for both the cleaning and drying operation.

Another object is to provide a simple and efficient scrubbing machine which is adapted to remove substantially all of the liquid from a surface.

Still another object is to provide a scrubbing machine of the above type having novel and improved details of construction and features of operation.

Various other objects and advantages will be apparent as the nature of the invention is more fully disclosed.

The scrubbing machine of the present invention comprises a suction nozzle containing a blade or other scrubbing appliance, a suction device including a suction-pressure pump and a valve controlling the flow of liquid to and from the nozzle, and a support or handle containing a flexible conduit which may be connected to a source of cleaning liquid such as soapy water and a similar conduit which may be connected to a waste receptacle or drain. In the embodiment disclosed herein for the purpose of illustrating the invention, the machine is mounted on wheels and is adapted to be moved over the floor in the manner of a vacuum cleaner, but it may also be made in other forms and sizes for cleaning floors, windows and the like.

The machine is controlled by a hand lever which controls the suction pump and also actuates the valve which selectively connects the supply and drain conduits to the nozzle through the valve and pump mechanisms. In one operative position of the hand lever and valve, cleaning liquid from the supply conduit is drawn

2

through one valve passage into the pump which discharges the liquid through another valve passage into the nozzle, thus wetting the floor or other surface which is then scrubbed by moving the machine back and forth like a vacuum cleaner. In another operative position of the hand lever and valve, the liquid on the floor is drawn up by suction through the nozzle and one valve passage into the pump which discharges it under pressure through another valve passage and the outgoing flexible conduit to the drain.

Although the novel features which are characteristic of this invention are set forth more in detail in the claims appended hereto, the nature and scope of the invention may be better understood by referring to the following description, taken in connection with the accompanying drawings forming a part thereto, in which a specific embodiment has been set forth for purposes of illustration.

In the drawings:

Fig. 1 is a side elevation of a portable floor scrubbing machine embodying the present invention;

Fig. 2 is an enlarged view of the upper handle, partly broken away to show the control mechanism;

Fig. 3 is a broken front elevation of the nozzle and suction device;

Fig. 4 is a transverse sectional view of the nozzle, showing the position of the floating blade when the nozzle is lifted off the floor;

Fig. 5 is a longitudinal sectional view through the machine, showing the motor, pump and valve mechanisms; and

Figs. 6, 7 and 8 are enlarged vertical sectional views of the valve mechanism of Fig. 5, showing same in different operative positions.

In the following description certain specific terms are used for convenience in referring to the various details of the invention. These terms, however, are to be interpreted as broadly as the state of the art will permit.

In the drawings, Fig. 1 shows a portable floor scrubbing machine comprising a suction nozzle 1 having a flared body portion 2, a suction device 3 and a handle 4 containing a flexible conduit 5 which may be connected to a source of cleaning liquid such as soapy water, and a similar conduit 6 which may be connected to a waste receptacle or drain.

The handle 4 of the machine carries a pivoted control lever 7 actuating a micro-switch 8 and a Bowden wire 9 which control the operation of

the suction device 3, as hereinafter more fully described. For the present it is sufficient to say that whenever lever 7 is moved upwardly from the normal inoperative position shown in Fig. 2, it actuates the micro-switch 8 and thereby energizes the suction device 3. Furthermore, when lever 7 is depressed part way cleaning fluid from conduit 5 is pumped to the flared body portion 2 of the nozzle, whereas when lever 7 is fully depressed the suction device 3 draws liquid upwardly through the nozzle for drying the surface and discharges the liquid through conduit 6 to a drain.

Suction nozzle

The suction nozzle 1 illustrated herein is of the type disclosed in my application Serial No. 635,049 filed December 14, 1945, now Patent No. 2,516,246 dated July 25, 1950, and comprises a rear wall 10 (Fig. 4) integral with the flared body portion 2, a front plate 12 secured to the wall 10 by screws 13, and suitable end plates supporting wheels 14 (Figs. 1, 3, and 5) by means of which the device may be wheeled across the floor or other surface to be cleaned and maintained in proper spaced relation therewith.

The nozzle 1 contains a chamber 17 having an elongated opening 18 at the bottom for the passage of fluid between the chamber 17 and the surface to be cleaned. A passage 19 is formed in the rear wall 10 for conveying fluid to and from said chamber 17. The edges defining the opening 18 are thin and sharp to prevent the accumulation of dust and dirt thereon and are shaped to form seats for the floating rectangular blade 20. This floating blade 20, of resilient material such as rubber, extends centrally through the chamber 17 and has a longitudinally spaced series of circular transverse holes 21 and is provided with transverse slits 22 extending from said holes to the top of the blade to increase its longitudinal resiliency.

The resilient blade 20 is formed with longitudinal shoulders 23 on both sides thereof, which are shaped to engage the edges defining the opening 18 of the nozzle to seal said opening and also to limit the outward movement of the floating blade. Coil springs 24 are mounted in the chamber 17 between the top of said chamber and the top of the blade 20, contacting the portions of the top surface of the blade between the transverse slits 22. These springs 24 are positioned in holes 25 in the front plate 12 of the nozzle. The blade 20 projects outwardly through the opening 18 and has a lower resilient scraping surface 26 which is adapted to engage the surface to be cleaned. The blade is slightly narrower than the opening 18 and thus provides a space for the passage of fluid on one side or the other of the blade as the blade slides back and forth over the surface which is being cleaned. In the embodiment illustrated in Fig. 4, an insert 27 of abrasive material such as pressed copper wool or the like, which has desirable cleaning properties, extends along the entire length of the bottom scraping surface 26 of the blade.

In operating the floor scrubbing machine shown in Figs. 1 to 4, the blade 20 is retracted by contact with the floor to provide a fluid passage to the chamber 17. The hand lever 7 may be first actuated to supply liquid such as soapy water from the conduit 5 to the nozzle and thence through the chamber 17 and around the blade 20 to the floor. The machine is then pushed

back and forth over the floor to scrub the same, the copper wool 27 assisting in this scrubbing operation. At the end of the scrubbing operation, the hand lever 7 is actuated to apply suction to the nozzle. The blade 20 scraping along the surface causes the water to pile up at its leading side around the opening 18 and the suction draws this water into the chamber 17 and through the passage 19 into the flared body 2 for discharge through the conduit 6. I shall now describe the construction and operation of the suction device 3 for accomplishing the foregoing operations.

The suction device 3 shown in Fig. 5 comprises an electric motor 30, a combination suction and pressure pump 31, and a valve mechanism 32. The motor 30 comprises the field pieces 33, armature 34, shaft 35, and stationary cone or hood 36 through which air is discharged for the purpose of cooling the motor as herein-after described.

Suction-pressure pump

The suction-pressure pump 31 is of the type disclosed in my application Serial No. 641,254 filed January 15, 1946, now Patent No. 2,470,319 dated May 17, 1949, and includes a rotary casting or plate 38 secured to motor shaft 35, and a multiple stage rotary suction fan 39 comprising two series of fan blades 40 and 41 which are secured to the shaft 35 on opposite sides of a stationary baffle 42. A rotary cylindrical casing 43 having a lower flared wall 44 is secured to the plate 38, as shown in Fig. 5, and will therefore rotate with said plate when the motor is running. A dished circular suction cut-off plate 46 is secured to the lower end of motor shaft 35 by a retaining nut 47, the outer periphery of this plate being spaced slightly from the cylindrical wall of rotary casing 43 to provide an annular opening 48 therebetween. In the operation of the device the fan 39 sucks air through the opening 48 and through a circular series of openings 49 in rotary plate 38, and this air, after passing over the stationary hood 36 of motor 30 and cooling the latter, is discharged through louvers 50 in the upper end of the suction casing 3.

A pair of stationary annular dished plates or cones 52 and 53 are mounted in the rotary casing 43, these cones being spaced apart slightly so as to form between them a restricted space or annulus 54 for the discharge of liquid which enters the rotary casing 43 in a manner hereinafter described. The cone 52 has its inner peripheral edge integral with a stationary cylinder 56 which extends through the housing 57 of valve mechanism 32. The cone 53 has its inner peripheral edge integral with a short cylindrical collar 58 secured to the inner wall of valve housing 57, and the upper portion of said inner wall of valve housing 57 is spaced from the stationary cylinder 56 to provide an annular valve passage 60 which communicates with the annulus 54 between the cones 52 and 53, as best shown in Figs. 6 to 8. Vanes 61 are secured between cones 52 and 53 to reduce the rotation of the liquid in annulus 54 due to rotation of the rotary casing 43. A felt ring 62 and rubber ring 63 in the upper end of valve housing 57 surround the collar 58 of cone 53 and seal the lower end of the flared wall 44 of rotary casing 43.

Before describing the construction of the valve mechanism 32 and the operation of the scrubbing machine as a whole, I shall briefly describe the operation of the suction-pressure pump 31, and for this purpose it is sufficient to assume that

liquid such as soapy water is sucked into the rotary casing 43 which is rotating along with motor shaft 35, carriage 38, suction fan 39 and suction cut-off plate 46. The liquid rotating in the rotary casing 43 lines the cylindrical wall of said casing and flows outwardly through the annulus 54 into the annular valve passage 60; while the air in casing 43 is drawn by fan 39 through the annular opening 48 between cut-off plate 46 and casing 43, and through opening 49 in carriage 38, and is expelled by the fan 39 through the louvers 59 in the upper end of the suction casing 3.

The layer of liquid lining the cylindrical wall of rotary casing 43 may continue to rise toward the center of the casing until it closes the annular opening 48 between cut-off plate 46 and the wall of the casing, at which time the suction of fan 39 will no longer act upon the casing 43 and no more liquid will be drawn into said casing until sufficient liquid has been expelled through annulus 54 and valve passage 60 to clear the opening 48 between cut-off plate 46 and casing 43. The centrifugal force prevents the suction from causing the liquid to rise appreciably toward the center in back of the plate 46. The size of the annular opening 48, which may be varied as described in my above-mentioned application Serial No. 641,254, thus determines the maximum depth and consequent pressure of the liquid in casing 43. The rotating mass of liquid in the casing 43 develops a high centrifugal force. The friction of the liquid entering the restricted annulus 54 retards the rotation of the liquid in the annulus, as do also the vanes 61, which reduces the centrifugal force acting on the liquid in the annulus and develops a pressure differential between the liquid in the casing (which is under high centrifugal force) and the liquid in the annulus (which is under low centrifugal force). This pressure differential is equivalent to a static head and develops the pressure necessary to drive the liquid out through the annular valve passage 60.

Valve mechanism

The lower end of valve housing 57 is secured to the body portion 2 of suction nozzle 1 by a coupling 65 and set screw 66, as shown in Fig. 5.

The stationary cylinder 56 depending from cone 52 is fixed to the inner cylindrical wall of valve housing 57 except for the upper portion thereof which is spaced from said wall to form the annular valve passage 60, as described above.

A spider 67 is secured to the lower inner wall of cylinder 56 and has an elongated integral tube 68 extending axially in said cylinder. One arm of the spider 67 contains an inlet port 69 communicating with the valve tube 68 and connected to the flexible conduit 5 which, as previously stated, may be connected to a source of cleaning liquid such as soapy water.

The valve tube 68 contains a hollow slideable valve plunger 70, the cylindrical wall of which contains a central valve port 71 which is adapted to register with the inlet port 69 in spider 67 when plunger 70 is in the mid-position shown in Fig. 7, at which time liquid from conduit 5 will pass through ports 69 and 71 into the hollow interior of plunger 70.

The valve plunger 70 is actuated by an elongated valve stem 73 which is threaded to a plug 74 secured in the lower end of said plunger. The lower end of valve stem 73 is pivoted to a lever 75 which is hinged at 76 to the inner wall of valve housing 57, as shown in Fig. 5. The Bowden wire 75

9, actuated by the control lever 7 on the handle 4 of the machine, has its lower end secured to the hinged lever 75. Accordingly, by manipulating the control lever 7, the lever 75 actuating valve stem 73 may be moved upon its hinge 76 and the valve stem 73 and plunger 70 may be raised or lowered in the valve tube 68. When the tension on Bowden wire 75 is released the hinged lever 75, stem 73 and plunger 70 are returned to their normal positions by a coil spring 77 which is compressed between the lever 75 and a spider 78 in valve housing 57 to which the lower end of tube 68 is secured, as shown in Fig. 5.

The flexible discharge conduit 6 which, as previously stated, may be connected to a drain, is connected directly to the annular valve passage 60 in the valve housing 57. The stationary cylinder 56, which constitutes the inner wall of the annular valve passage 60, contains an arcuate port 80 which is opposite the terminus of the conduit 6, as best shown in Figs. 6 to 8.

Slidably mounted within the upper portion of the stationary cylinder 56 is a unitary valve member 81 having the following parts: An outer cylindrical sleeve 82 which is in close sliding engagement with the cylinder 56 and contains an arcuate port 79 adapted to register with the arcuate port 80 in cylinder 56, and a circumferential series of arcuate slots 83 adjacent the top of said sleeve 82 for a purpose hereinafter described; a top plate 84 which is adapted to seat upon and seal the top edge of stationary cylinder 56 within the cone 52 when valve member 81 descends to its lower limiting position within said cylinder 56 as shown in Figs. 6 and 7; and a hollow axial tube or core 85 which is carried by the top plate 84 and is slidably mounted in the upper portion of valve tube 68 above the slideable valve plunger 70. The elongated valve stem 73 actuating plunger 70 extends upwardly through a spider 86 secured in the tube 85, and a light coil spring 87, compressed between the spider 86 and the upper end of stem 73, tends to hold the top plate 84 seated during the upward movement of the sleeve 82. A check valve 6a prevents return flow of liquid from the conduit 6.

Operation

Fig. 6 shows the valve mechanism in its normal idle state, that is, when the floor scrubbing machine is not operating. At such time the pivoted control lever 7 on the handle 4 of the machine is retracted as shown in Fig. 2, the micro-switch 8 is open, and the motor 39 is de-energized.

When the valve mechanism is in the idle state shown in Fig. 6, it will be noted that the valve stem 73 and its valve plunger 70 are in their lowermost position with plunger 70 closing the inlet port 69, hence liquid could not enter the machine from the inlet conduit 5 even if said conduit were connected to a source of liquid under pressure. In Fig. 6, furthermore, the slideable valve member 81 is in its "down" position with its top plate 84 seated upon and sealing the top edge of stationary cylinder 56 within the cone 52, and in this position the circumferential series of slots 83 in sleeve 82 of valve member 81 are completely closed by the surrounding stationary cylinder 56. At the same time the arcuate port 79 in the sleeve 82 of the valve member 81 is in registry with the arcuate port 80 in stationary cylinder 56, which port 80 is open to the annular valve passage 60 and hence to the drain conduit 6. In addition, attention is pa-

ticularly called to the fact that in Fig. 6 the top of the slidable valve plunger 70 in tube 68 is spaced from the bottom of the axial tube 85 of slidable valve member 81, hence it is possible for the plunger 70 to ascend an appreciable distance in tube 68 before striking the bottom of the axial tube 85.

In operating the scrubbing machine, the operator grasps the hand lever 7 (Fig. 2) and raises it part way, toward the handle 4 or until resistance to further depression is encountered (the reason for such resistance being explained below).

Raising of hand lever 7 closes micro-switch 8 in handle 4 and thereby energizes the motor 30 of suction device 3. It also exerts tension on the Bowden wire 9, thereby raising the hinged lever 75 in valve housing 57 and consequently raising the valve stem 73 and valve plunger 70 in the valve tube 68. The valve plunger 70 is raised until it strikes the bottom of the axial tube 85 of slidable valve member 81, at which time the hand of the operator encounters definite resistance to further movement of the hand lever 7. The operator therefore maintains the hand lever in this partly raised position as long as it is desired to wet the surface which is to be scrubbed.

Fig. 7 shows the valve mechanism in this position, with the top of valve plunger 70 engaging the bottom of the axial tube 85 of valve member 81, and with the central valve port 71 of plunger 70 registering with the inlet port 69 in spider 67 connected to the flexible conduit 5. This change in the position of valve plunger 70 and its stem 73 is the only difference between Fig. 7 and the "idle" position shown in Fig. 6.

The flexible conduit 5, as previously stated, may be connected to a source of cleaning liquid such as soapy water. Accordingly, since the motor 30 and suction fan 39 are now running, liquid is sucked from conduit 5 through ports 69 and 71, and the interior of valve plunger 70 and axial tube 85, into the rotary casing 43 of the suction-pressure pump 31. This liquid is carried around the cylindrical wall of casing 43 and is discharged through the annulus 54 between stationary cones 52 and 53, into the annular valve passage 60.

From valve passage 60 the liquid flows through arcuate port 80 in stationary cylinder 56 and arcuate port 79 in sleeve 82 of valve member 81, into the interior of said sleeve 82, and thence into the flared body portion 2 of the suction nozzle 1, as indicated by the arrows in Fig. 7. The liquid in valve passage 60 will fail to open the check valve 6a, but instead will drain through ports 80 and 79 to the nozzle 1. The liquid entering the nozzle flows through the chamber 17 thereof, and around the blade 20 to the floor, as previously described. The operator pushes the machine back and forth over the floor to scrub the same, and, of course, he may release the hand lever 7 and discontinue the feed of liquid during a portion of the scrubbing operation after sufficient liquid has been deposited on the floor.

At the end of the scrubbing operation the hand lever 7 is raised all the way to apply suction to the nozzle 1, as will now be described. The actuation of hand lever 7 to the limit of its movement exerts a tension on Bowden wire 9 which raises the hinged lever 75, valve stem 73 and valve plunger 70 to the upward limit of their travel. The valve plunger 70, in thus ascending through valve tube 68, strikes against

the bottom of the axial tube 85 of slidable valve member 81 and then raises the entire valve member 81 to the position shown in Fig. 8.

In the position of the parts shown in Fig. 8 5 the valve plunger 70 is raised to a point where its central valve port 71 no longer registers with the inlet port 69 connected to the flexible inlet conduit 5, and therefore, since inlet port 69 is now closed by plunger 70, liquid can no longer 10 enter the valve mechanism from conduit 5 even though said conduit is still connected to the source of cleaning liquid.

In Fig. 8, furthermore, the cylindrical sleeve 82 of slidable valve member 81 is elevated to a 15 point where the arcuate port 79 in said sleeve no longer registers with the arcuate port 80 in stationary cylinder 56, the said port 80 now being closed by the sleeve 82, as illustrated. In addition, the top plate 84 of slidable valve member 20 81 is now raised above the top edge of stationary cylinder 56 and the circumferential series 25 of slots 83 in sleeve 82 (which were closed by the surrounding stationary cylinder 56 in Figs. 6 and 7) are now raised above the top of cylinder 56 and are open to the stationary cone 52, as illustrated in Fig. 8.

With the parts in the position shown in Fig. 8, the motor 30 and suction fan 39 are running, and, as previously described, the movement 30 of the scrubbing machine over the floor causes liquid on the floor to pile up at the leading side of the scraping blade 20 and around the opening 18 in the nozzle 1. The suction of fan 39 draws this liquid into the body portion 2 of the nozzle 35 and thence upwardly through stationary cylinder 56 of valve mechanism 32, and through sleeve 82 of valve member 81 and the circumferential slots 83 thereof, into the rotary casing 43. This 40 liquid is carried around the cylindrical wall of casing 43 and is discharged through the annulus 54 between stationary cones 52 and 53, into the annular valve passage 60. From valve 45 passage 60, the liquid, which is under considerable pressure, is pumped through flexible conduit 6 to the drain.

Although a specific embodiment has been shown and described herein for purposes of illustration, it will be evident to those skilled in the art that the invention is capable of various 50 modifications and adaptations within the scope of the appended claims.

What is claimed is:

1. A scrubber comprising a nozzle to be pushed over a surface, a suction-pressure pump having an intake side and a discharge side, a liquid supply duct and a liquid discharge duct, and valve means having means in one position to connect the intake side of said pump to said liquid supply duct and the discharge side of said pump to said nozzle for scrubbing and in another position to connect the intake side of said pump to said nozzle and the discharge side of said pump to said liquid discharge duct for drying said surface, said pump having a suction device and a centrifugal liquid separator to separate the liquid, said discharge side being connected to discharge the separated liquid directly from said separator without passing through said suction device.

2. A scrubber comprising a nozzle to be pushed over a surface, a suction pressure pump having an intake side and a discharge side, a liquid supply duct and a liquid discharge duct, and valve means having means in one position to connect the intake side of said pump to said

liquid supply duct and the discharge side of said pump to said nozzle for scrubbing and in another position to connect the intake side of said pump to said nozzle and the discharge side of said pump to said liquid discharge duct for drying said surface, said valve means comprising a housing having a cylindrical wall and a concentric tube spaced to form concentric inner and outer passages, said outer passage communicating at one end with said nozzle and at its other end with the intake side of said pump, said inner passage communicating at one end with the intake side of said pump, a valve plunger closing the other end of said inner passage and slideable in said tube, a port in said tube connected to said liquid supply duct and closable by said plunger, a closure for said other end of said outer passage, a port in said cylindrical wall, a sleeve closing said last port, a passage connecting the discharge side of said pump with said liquid discharge duct and with said last port, and interconnected actuating means for said sleeve and plunger connected in one position to open both of said ports for supplying liquid from said liquid supply duct through said pump to said nozzle, in a second position to close both of said ports, and in a third position to close said first port and open said second port and said closure for applying suction to said nozzle and discharging liquid therefrom through said discharge duct.

3. A scrubber, as set forth in claim 2, in which said closure comprises an annular plate seating on said cylindrical wall and said tube and carrying said sleeve.
- 5 4. A scrubber, as set forth in claim 3, in which said annular plate carries a core slideable in said tube and positioned to be engaged by said plunger for lifting said closure plate.

EDWARD O. NORRIS.
